UNITED STATES PATENT OFFICE.

CHARLES L. HOOEY, OF DOVER, NEW JERSEY.

EXTRICATING MEANS FOR VEHICLES.

Application filed September 17, 1923. Serial No. 663,310.

To all whom it may concern:

Be it known that I, CHARLES L. HOOEY, a citizen of the United States, and a resident of Dover, county of Morris, and State of New Jersey, have invented certain new and useful Improvements in Extricating Means for Vehicles, of which the following is a specification.

This invention relates to an improved means and method for extricating a motor out of a ditch or other depression and is adapted for use with a service car or can be carried in a passenger car, the invention being directed to the provision of a rope which is secured in advance of the car and is wrapped around a part of the rear wheel and this wheel is then raised from contact with the ground and supported in this raised position on a rolling carriage. The invention is illustrated in the accompanying drawings, in which Figure 1 is a top view of a ditched car with the propelling and supporting devices in position. Figure 2 is a partial section showing the car partly raised on one side. Figure 3 is a similar view showing the car supported on the raised side by a carriage. Figure 4 is a section of the carriage on a platform. Figure 5 is a face view of a drum attachable to a rear wheel and Figure 6 is a partial section of a wheel with the drum in place. Figure 7 is a partial section of a modified form of drum.

In said drawings, the automobile is illustrated as ditched at the side of a road and in Figure 1, the dotted outline 10, represents the body of the car and the front and rear wheels and associated parts are shown in full lines. The car is hauled forward by a rope 12 which is provided with a pair of pulleys 13 and 14, the rope having one end detachably secured to the pulley 14 as by knotting it as at 15. The other end of the rope is wrapped around a part of one of the rear wheels as at 16 and to provide such part, I usually fasten a drum 17 to the outer face of the wheel. The drum 17 can be detachable as in Figures 5 and 6, having the flange 18 with the holes 19 through which the bolts 20 pass the bolts passing between the spokes of the wheel and thus securing the drum in place. In other cases, as in disc wheels, the drum can be permanently attached or made part of the wheel, as in Figure 7 and when not in use covered by an

ornamental cap 21 which can be screwed on the shoulder 22.

If the car is to be drawn out at a rather sharp angle, the rope is secured by the pulley 13 to a post or staff 23 driven into the ground or any fixed support as a post or tree and the pulley 14 is caught over the front part of the chassis, as will be seen from Figure 1.

If the car is to be propelled at a slight angle, the rope is unfastened at 15 withdrawn once through pulley 13 and is passed over a drum 24 on the other rear wheel. This drum is a duplicate of 17. The pulley 14 in such case is secured to a fixed point 25.

If the car is to be pulled straight ahead, the reaches of the rope at 26 and 27 are at the same angle by moving the point 25 more to the side. This will be evident from the showing in broken lines in Figure 1.

The usual necessity, is however, to arrange the rope as shown in full lines in Figure 1 using only the drum 17 for hauling and in this case the wheel 27 on this side of the car is raised from contact with the mud or ground since its traction when it rests on the ground prevents it from revolving fast enough to take up the rope on a small drum. It is therefore necessary by my method to raise this wheel as by a jack 28 and when so raised to support it in raised position so that it can be moved in such raised position. I do this by placing a platform usually a board or boards 29 which are shown raised on blocks 30. The boards can be hinged as at 31 for storage in the car. A carriage 32 has wheels or rollers 33 and has means for detachably securing it to the housing 34 of the rear axle or to some other equivalent fixture. The form shown comprises hooks 35 and 36, 35 being single and 36 having a double hook which can be swung over the housing and then moved longitudinally to clamp the housing by means such has the nuts 37.

With this apparatus and method, I can run the rear wheel 27 at a high speed to utilize the power of a small drum to wind up the rope for hauling. This could not be done with the wheel 27 on the ground since the wheel would be limited in its revolutions per minute by its contact with the ground and the drum could not take up on the rope.

The rolling carriage maintains the wheel

in raised position to permit the above function and also acts to advance the car under the influence of the hauling rope.

I claim:

- 5 A means for extricating ditched motor cars comprising a rope adapted to be secured around the driving wheels of the car and to be secured to a point beyond the car, a portable platform, and a carriage adapted to be
10 detachably secured to the rear axle housing

and to form a rolling means for one side of the car on the said platform, the carriage being disposed so as to cause the wheel of the car to clear the ground whereby the speed of the car is controlled entirely by the 15 coiling of the rope.

In testimony that I claim the foregoing, I have hereto set my hand, this 14th day of September, 1923.

CHAS. L. HOOEY.
